UNITED STATES PATENT OFFICE

WILLIAM BARK, OF GARY, INDIANA, ASSIGNOR TO NATIONAL TUBE COMPANY, A CORPORATION OF NEW JERSEY

TUBE PIERCING AND EXPANDING PLUG

Application filed December 4, 1929. Serial No. 411,540.

This invention relates to expanding plugs for use in the manufacture of seamless tubes and has for its object the provision of a novel form of two-part plug designed so that the nose portion which receives the major portion of the wear may be readily replaced when worn.

Heretofore, plugs of this class have generally been formed in one piece from a casting or forging and when worn, the whole 10 plug was necessarily destroyed.

With the present invention it is only necessary to replace a very small part of the plug when it becomes worn, thus providing a considerable saving in cost of plugs.

In the drawings—

Figure 1 is a sectional view through the forward end of an expanding bar and plug constructed in accordance with this invention, the section being taken on the line I—I of Figure 2.

Figure 2 is a transverse section taken on the line II—II of Figure 1.

Figure 3 is a transverse section taken on the line III—III of Figure 2.

Referring more particularly to the drawings the numeral 2 designates the plug bar as a whole, which is of ordinary design, and has its forward or plug end reduced, as at 3, to form a plug supporting spindle which terminates at its rear end in a shoulder 4. The bar 2 has a central bore 5 to permit the circulation of a cooling fluid therethrough for controlling the temperature of the bar.

A plug A is removably mounted on the reduced or spindle end 3 of the bar 2 and has its rear end abutting the shoulder 4. The plug A is formed in two parts as will be seen by reference to the drawings in which the 35 numeral 6 designates the body portion of the plug while the numeral 7 designates a removable nose portion thereof.

The body portion 6 of the plug has its forward end reduced in diameter, as at 8, to receive the nose 7 which is longer than the portion 8 and has its forward end extending downwardly in front of the forward end of the plug body, as at 10. The reduced portion 8 terminates at its rear end in a shoulder 9.

The reduced diameter portion 8 of the plug body 6 is provided with bayonet slots 12 and 13 at diametrically opposite points which are adapted to receive lugs 14 and 15, respectively, formed integral with and projecting into the bore of the nose 7 at the rear end thereof.

It will be seen that the nose portion 7 of the plug A may be readily mounted on the plug body 6 by alining the lugs 14 and 15 with the grooves 12 and 13 and then sliding the nose member rearwardly until its rear end engages the shoulder 9. The nose member will then be turned or rotated to move the lugs into the lock ends of the slots 12 and 13 thus preventing displacement of the 55 nose 7.

When it is desired to remove the nose 7 it is only necessary to rotate it to move the lugs 14 and 15 into the main or entering portions of the grooves 12 and 13 and then to withdraw the nose from the body 6.

Since substantially all of the wear is on the nose of the plugs used in expanding or otherwise working seamless tubes the advantage of having such nose portion readily renewable will be appreciated.

While I have shown and described one specific embodiment of my invention it will be understood that I do not wish to be limited thereto since various modifications may be 75 made without departing from the scope thereof, as defined in the appended claims.

I claim:

1. The combination with a plug-bar for seamless tube machines having one end reduced forming a plug receiving shank terminating in a shoulder, of a plug mounted on said shank and abutting said shoulder, said plug having its forward end reduced in diameter to receive a removable nose, bayonet-like slots formed in said reduced diameter end portion of said plug, and a removable nose member mounted on said reduced diameter end of said plug, said nose member being provided with lugs adapted to be locked in said bayonet-like slots by a rotation of 85 said nose member.

2. The combination with a plug-bar for seamless tube machines having one end reduced forming a plug receiving shank ter-

minating in a shoulder, of a plug mounted on
said shank and abutting said shoulder, said
plug having its forward end reduced in di-
ameter, a removable nose on said reduced di-
ameter end of said plug, and means for re-
movably locking said nose portion on said
reduced diameter end of said plug.

5 In testimony whereof, I have hereunto set
my hand.

WILLIAM BARK.
